Primary Examiner — Prabhakar Deshmukh*(74) Attorney, Agent, or Firm* — Foley & Lardner LLP(57) **CLAIM**

We claim the ornamental design for a padlock, as shown and described.

DESCRIPTION

FIG. 1 is a top, front, left perspective view of a padlock showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines indicate unclaimed portions and form no part of the claimed design. The broken away portions of the shackle indicate undetermined length and the portions between the broken away portions of the shackle form no part of the claimed design.
